DESIGN FOR A MANICURE BOWL OR SIMILAR ARTICLE

Armond E. Sutton, Pasadena, Calif.

Application September 29, 1941, Serial No. 103,546

Term of patent 14 years

To all whom it may concern:

Be it known that I, Armond E. Sutton, a citizen of the United States, residing at Pasadena, county of Los Angeles, State of California, have invented a new, original, and ornamental Design for a Manicure Bowl or Similar Article, of which the following is a specification, reference being had to the accompanying drawing, forming part thereof.

Fig. 1 is a top perspective view taken from one end of a manicure bowl or similar article showing my new design;

Fig. 2 is a top perspective view thereof taken from the end opposite that shown in Figure 1; and

Fig. 3 is a sectional view thereof taken on line III—III of Fig. 1.

I claim:

The ornamental design for a manicure bowl or similar article, substantially as shown.

ARMOND E. SUTTON.
